[57] **CLAIM**

The ornamental design for an audio disc player, as shown and described.

DESCRIPTION

FIG. 1 is a perspective view of an audio disc player showing our new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear elevational view thereof; and,

FIG. 8 is a perspective view of a second embodiment of an audio disc player wherein the lid portion of the first embodiment is in the open position.

The remaining views of the inside of the audio disc player which are not visible in FIG. 8 form no part of the claimed design.
